(57) **CLAIM**

The ornamental design for a fixing hardware for roof panel, as shown and described.

DESCRIPTION

FIG. 1 is a top, perspective view of the fixing hardware for roof panel, showing my claimed design;

FIG. 2 is a second, top view of the fixing hardware for roof panel of FIG. 1;

FIG. 3 is a front view of the fixing hardware for roof panel of FIG. 1;

FIG. 4 is a rear view of the fixing hardware for roof panel of FIG. 1;

FIG. 5 is a first side view of the fixing hardware for roof panel of FIG. 1;

FIG. 6 is a second side view of the fixing hardware for roof panel of FIG. 1;

FIG. 7 is a top view of the fixing hardware for roof panel of FIG. 1; and,

FIG. 8 is a bottom view of the fixing hardware for roof panel of FIG. 1.

The dash-dash broken lines illustrate portions of the fixing hardware for roof panel. The long dash-short dash broken lines illustrate the bounds of the claimed design. None of the broken lines form part of the claimed design.
